NEEDLE LEVELER AND LATCH OPENER

Oscar Fregeolle, Central Falls, R. I., assignor to
 Hemphill Company, Central Falls, R. I., a corporation of Massachusetts

Application March 23, 1945, Serial No. 584,307

6 Claims. (Cl. 66—111)

This invention relates to a needle leveler and latch opener for circular, independent needle, knitting machines or for any other type of machine for which it is adapted. Since this invention is particularly useful on two cylinder machines, it will be shown and described herein in relation to such type of machine.

As is well known, knitting machines of the type having opposed coaxial cylinders employ a needle having a hook and latch at each end, the upper hook and latch being used for knitting in the lower cylinder and the lower hook and latch for knitting in the upper cylinder. Such needles are operated by sliders in each cylinder which are adapted to be coupled to the corresponding hook of the needle.

Whenever it becomes necessary to transfer a needle from the lower to the upper cylinder, the upper latch must be open so that the corresponding slider in the upper cylinder can engage the upper hook of the needle. If a needle has no yarn loop in its hook, as when starting up on bare needles or when beginning a new stocking of string work, there is nothing to insure that the latch will open. Therefore, a latch opener is required. As is well known, such an opener must enter the very small space between the hook and the latch. Consequently, the needles must all be positively positioned at a certain level and also in correct radial alignment or the latch opener may miss this space and strike the needle or the latch with resulting damage to the needle and to the fabric.

A double ended, slider operated needle is not likely to reach this level automatically because, since it must be possible to uncouple the slider from the needle, a certain amount of play between the slider and the needle hook is essential. Therefore, one needle may be a little higher than another. By the present invention all of the needles are brought to a definite level relative to the position of the latch opener so that perfect operation of the latch opener is assured.

One form of the invention is shown in the accompanying drawings of which:

Fig. 1 is a view in section on the line 1—1 of Fig. 2 showing the relation between a double ended needle and its lower cylinder slider and how the needle leveler functions to level all of the needles.

Fig. 2 is a view from outside the needle cylinder of the same parts; and

Figs. 3 and 4 are a plan and elevation respectively of the needle leveler and latch opener and their operating mechanisms.

In Fig. 1 the lower and upper cylinders of the machine are shown at 1 and 2, respectively. In the lower cylinder is a needle 3 having an upper hook 4 and latch 5 and a lower hook 6 and latch 7. The needle is connected to a slider 8 in the lower cylinder by means of hook 9 which engages with hook 6 of the needle. As is well known, the slider below hook 9 must be cut away somewhat so that it can be coupled to and uncoupled from the needle. A ledge 10 results. In consequence, there is a space 11 on which the needle may be anywhere so that the level of the upper hook is uncertain within these limits.

Since the latch opener has necessarily a fixed position and since the space between the hook and latch of the needle is very small any such variations in needle position would be disastrous because the latch opener instead of entering the proper space might hit the needle or the latch with consequent damage to the needle and fabric.

To prevent this the present invention was made. It consists primarily of a needle leveler 12 composed of a mounting plate 13 and a leveling element 14. This latter element 14 consists of a horizontal plate, the underside of which is curved as shown at 15 to substantially correspond with the curvature of the end of the upper needle hook. Its position is such that it overlies the path of the needles at the height at which the needles must be positioned for proper operation of the latch opener and also so that it will prevent the upper ends of the needles from tilting outwardly from their slots.

Below the slider 8 is a cam 16 having an easy slope 17 and of a height sufficient to raise the sliders sufficiently to bring the needles into contact with surface 15 of the needle leveler when the lower hook of the needle is resting against the ledge 10 of the slider. In consequence, every needle will be positioned at exactly the same height so that a latch opener positioned directly below it must open the latches and cannot possibly strike the needle or its latch. Since this device is intended to operate only upon lower cylinder needles and usually only just before they are transferred to the upper cylinder, means must be provided to move it out of the way of the needles. One means for this purpose is shown in Figs. 3 and 4. As shown, the needle leveler 14 is mounted upon a slide 18 by means of plate 13. Slide 18 is so mounted within guide 19 as to be slidable radially of the cylinder. Latch opener 20 shown as a round rod is also adjustably attached to slide 18. At the other end of slide 18 is a stud 21 engaging with one end of a bell

crank 22, the other end of which engages with one end of another bell crank 23. Bell crank 23 is connected by suitable operating levers indicated in Fig. 4 by the rod 24 by means of which the mechanism is operated to withdraw or project the needle leveler and latch opener whenever desired.

I claim:

1. For a knitting machine having a cylinder with slots for needles, a needle leveler which includes means for raising needles to a predetermined level, means engageable with the hooks of needles for preventing needles so raised from moving to a higher level and means engageable with the hooks of needles for aligning said needles radially in their cylinder slots.

2. For a knitting machine a combined needle leveler and latch opener which includes a latch opener adapted to open the latches of needles when they are raised to a certain level, means for raising said needles to that level and means associated with the latch opener for preventing the needles so raised from moving above said level.

3. For a knitting machine a combined needle leveler and latch opener which includes a latch opener adapted to open the latches of needles when they are raised to a certain level, means for

raising said needles to that level and means associated with the latch opener for preventing the needles so raised from moving above said level, said latch opener and said needle leveler being retractable.

4. For a knitting machine having two coaxial superposed needle cylinders and needles adapted to be transferred from one cylinder to the other, a needle leveler adapted to be positioned above said needles when in the lower cylinder and means for raising said needles into contact with said leveler whereby all needles so raised will be positioned at the same level.

5. For a knitting machine having two coaxial superposed needle cylinders and needles adapted to be transferred from one cylinder to the other, a needle leveler adapted to be positioned above said needles when in the lower cylinder and means for raising said needles into contact with said leveler whereby all needles so raised will be positioned at the same level, said means consisting of a cam and sliders.

6. For a knitting machine a combined needle leveler and latch opener according to claim 2 which also includes means engaging the hooks of needles for aligning said needles radially in their cylinder slots.

OSCAR FREGEOLLE.
